UNITED STATES PATENT OFFICE.

ERIK L. NYLUND, OF DETROIT, MICHIGAN.

RAILWAY SWITCH.

1,425,680.

Specification of Letters Patent. Patented Aug. 15, 1922.

Application filed July 26, 1921. Serial No. 487,690.

To all whom it may concern:

Be it known that I, ERIK L. NYLUND, a citizen of the United States, and resident of Detroit, in the county of Wayne and State of Michigan, have invented certain new and useful Improvements in Railway Switches, of which the following is a specification.

This invention relates to railroad switches, having reference more particularly to an improved operating mechanism for swinging the switch rails.

The invention has for an object the provision of a mechanism of this character which may be operated from the front of a moving car or by the engineer from his cabin, for purposes of either opening or closing the switch, when the train approaches from the points of the swinging switch members; a further object being to provide a durable and simply constructed mechanism of this character which comprises a novel assemblage of elements so arranged that they may be operated without jarring action.

In carrying out my invention I employ a bumper comprising a pivoted pinion having a fixed radial arm and two spring-yielding arms, a rack-bar meshing with said pinion and connecting the two swinging ends of the switch rails, spring means for holding said rack-bars against accidental lateral movement, and means mounted on the ends of a car for turning said pinion in either direction for alternately opening and closing the switch, all as hereinafter fully described and specifically set forth in the appended claims.

In the accompanying drawings forming part of this specification, Figure 1 is a plan view of a section of a railway having my improvements attached.

Fig. 2 is a fragmentary plan view drawn on an enlarged scale;

Fig. 3 is a cross sectional view taken on the line 3—3 of Fig. 2;

Fig. 4 is a fragmentary sectional view taken on the line 4—4 of Fig. 1;

Fig. 5 is an end view of a freight car having my improved operating means attached;

Fig. 6 is a detail sectional view taken on the line 6—6 of Fig. 5, and drawn on an enlarged scale;

Fig. 7 is a fragmentary plan view of the lever mechanism for operating the switch;

Fig. 8 is a front view of said lever mechanism; and

Fig. 9 is a fragmentary cross section taken on the line 9—9 of Fig. 5, and drawn on an enlarged scale.

In the drawings 2 indicates a toothed pinion having an integral hub 3 which is mounted on a vertical bolt 4 fixed to a base plate 5 which is secured on a relatively wide tie 6.

Formed integral with the hub 3 is a radial arm 7 having on each side, near its free end, a stud 8. In swinging relation with the bolt 4 are bumper arms 9 and 10, the arm 9 having a stud 9^a, and the arm 10 having a stud 10^a. Fixed between the said studs of the arm 7 and the studs of the arms 9 and 10 are normally expanded helical springs 11, whereby the arms 9 and 10 are normally maintained at right angles to each other.

Engaging the teeth of the pinion 3 is a rack-bar 12 which is flexibly jointed, at its end, to the switch rails 13, by means of bearings 14 which are fixed to said rails. Said rack-bar 12 is flexibly coupled to an adjacent tie 6^a, by means of a flexible coupling 15, comprising the two telescopically connected members 16 and 17, the member 16 is pivoted to the tie 6^a, by means of a bolt 16^a, and the member 17 is pivoted to the rack-bar 12 by means of a bolt 17^a, and guide-braces 12^a are mounted between the ties 6 and 6^a to insure smooth sliding movement of the rack-bar 12. Extended within the coupling 15 is a contractile spring 18 having a normal tendency to extend the coupling 15, whereby the rack-bar is maintained set and accidental lateral movement thereof is prevented.

The switch rails 13 are further connected by means of cross bars 19 which are pivotally connected to bearings 20 fixed to said switch rails. Bearing plates 13^a are countersunk in the ties, whereby smooth surfaces are provided over which the switch sections may freely move without liability of wearing the ties, and provision may be made for lubricating said bearing plates.

As a means for turning the pinion 2, I employ vertically adjustable bars 21 and 22, which reciprocate within guideways 23 of a depending hanger 24, which is securely fixed to the ends of the cars, as 25. The presser bars are respectively provided with a contact shoe 21^a, 22^a which are obliquely extended for respectively engaging the bumper arms 9 and 10, for operating the

switch, as hereinafter described. These presser bars are operated by means of levers 28 and 29 which respectively swing on pivots 28^a and 29^a, said levers being each provided with a slot 30, to allow for their swinging movements, and they are connected by means of a rocking lever 26 and links 25^a. Other means may be employed for operating the presser bars either from a car 10 or from the engine cab, and I may provide means for locking the presser bars in a neutral or inoperative position on long runs when it is not desired to operate a switch.

In the operation of my invention, when a 15 train or car is moving in the direction of the arrow *a*, Fig. 1 of the drawings, and it is desired to open the switch it is simply necessary to lift the lever 28, and thereby move the presser bar 21 downwardly, thus bringing the shoe 21^a in alignment with the bumper arm 9, whereby it swings the bumper around in the direction of the arrow *b*, for a sufficient distance to open the switch.

It is noteworthy that the shock of the 25 first contact with the bumper arm is absorbed by the springs 11, and then the forward movement of the contact shoe carries the bumper around and turns the pinion 2 sufficiently to open the switch and bring the 30 arm 10 into position for use, and it remains open until a following car or train carrying a presser bar 22 operates to again close the switch by transmitting movement through the arm 10 to the rack-bar 12, in an opposite direction. When it is not desired to

operate the switch the shoes 21 and 22 are moved into a neutral position above the level of the bumper arms 9 and 10.

I do not wish to be understood as confining myself to the specific details of mechanical construction and correlation of the elements of my improvement as herein shown and described, as under the spirit of my invention I believe that I am entitled to employ such variations as may rightly fall 45 within the scope of the appended claims.

Having thus described my invention, what I claim as new and desire to secure by Letters Patent, is:

1. In a railway switch mechanism, a 50 pivoted bumper comprising a pinion, a rigid arm and yielding arms, and a rack-bar meshing with said pinion, said rack-bar connecting the two ends of switch rails, and spring means for holding said rack-bar 55 against accidental lateral movement, and means for swinging said bumper.

2. In a railway switch mechanism, a pivoted bumper comprising a pinion, a rigid arm and yielding arms, and a rack-bar 60 meshing with said pinion, said rack-bars connecting the two ends of switch rails, and spring means for holding said rack-bars against accidental lateral movement, and a 65 lever and presser bar mechanism for operating said bumper.

Signed at Detroit in the county of Wayne and State of Mich., this 14th day of July A. D. 1921.

ERIK L. NYLUND.
